(57) **CLAIM**

The ornamental design for a wall mount hanger, as shown and described.

DESCRIPTION

FIG. 1 is a front perspective view of the wall mount hanger of the present invention showing our new design;

FIG. 2 is a side elevational view thereof with the phantom lines depicting solely environmental structure and forming no part of the claimed design;

FIG. 3 is bottom plan view thereof;

FIG. 4 is a front elevational view thereof;

FIG. 5 is a rear elevational view thereof; and,

FIG. 6 is a top plan view thereof.
